PUMP

William T. Livermore, Grosse Pointe, Mich.

Application November 7, 1938, Serial No. 239,199

7 Claims. (Cl. 103—135)

This invention relates to pumps of the so-called vane type.

Several types of rotary pumps employ rotor propelled vanes for the purpose of creating a pumping action in a pump housing having a bore of approximately circular shape. In general these vane type pumps have been of two types, one in which the vanes are formed by a member which extends completely through the rotor which carries the vanes for rotation, the vane member being allowed to slide in the diametrically positioned opening in the rotor so that the projecting ends of the vane will contact the wall of the pump chamber to carry fluid from an inlet to an outlet and thereby create a pumping action. In this so-called through type of vane pump, the pump chamber is so shaped that the ends of each vane are continuously in contact with the wall of the pump chamber. Another type of vane construction commonly used is that of two short vanes projecting from the openings in the rotor with a spring in the center of the rotor to hold each of the two opposed vanes in contact with the wall of the pump chamber. It is to be noted that in both of the above types the vanes are generally located in pairs diametrically opposed to each other and the vanes are held in openings in the rotor with relatively close clearance so that there is no tendency of the vanes to move circumferentially. It is also a characteristic of the above mentioned vane types of pumps that the so-called working arc between the inlet and outlet ports must be substantially equal to the distance between the vanes carried by the rotor. For, if the distance between vanes should be reduced below the equality, a pressure would be built up between two vanes during the working arc. Another way of stating this problem is that in the conventional vane type of pump with circular bore with no means of equalizing pressure between vanes only one vane can be pushing fluid in the working arc at one time since there must be a free passage to the outlet to compensate for differences in volumes enclosed between adjacent vanes during the working arc.

It is also a characteristic of the vane types of pumps above mentioned that the spacing between the vanes around the circumference of the rotor is necessarily equal since, as above outlined, each of these spaces must bear the same relation to the distance between the inlet and outlet ports. In some instances such a construction has been found responsible for excessive noise produced by the pump since the equal spacing sometimes sets up a resonance with a consequent hum.

In general, the operation of the conventional types of vane pumps has been quite satisfactory. However, since many of the parts require very accurate machining to assure this satisfactory operation, there would be a considerable saving in manufacturing cost if a pump could be devised wherein the parts would be both reduced in number and would not require great accuracy in dimensions.

It is therefore a primary object of the present invention to provide an efficient pump of such simplicity of construction that comparatively few dimensions are required to be held to very close tolerances, thereby avoiding expensive machining operations and effecting material saving in manufacturing cost without reducing the efficiency of the pump.

It is a further object to make possible the construction of a pump with a circular bore having means to compensate for difference in fluid displacements by two or more vanes which may be operating in the working arc at one time, thereby making it unnecessary to maintain any definite relation between the arcuate distance from inlet to outlet and the arcuate distance between vanes.

It is another object to reduce the noise produced by a vane type pump by a construction wherein the plurality of vanes are unequally spaced around the periphery of the pump rotor.

It is a further object to allow free flow of fluid around the surfaces of floating vanes loosely carried in notches in the periphery of a rotor thereby assuring distribution of fluid between a plurality of vanes operating in the working arc at one time and making possible an increase in the number of vanes and an unequal spacing to reduce noise, such an advantage being accomplished with a construction employing a minimum of parts, some of which require expensive machining operations in their manufacture.

It is another object to make possible the construction of a pump wherein a plurality of slipper type vanes are loosely carried in notches in the periphery of the pump rotor, the said rotor serving primarily to drive the vanes while centrifugal force and fluid pressures existing in the pump chamber are primarily utilized to hold substantially the entire sealing surface of the vanes in continuous contact with the wall of the pump chamber for producing a pumping action.

It is also an object to provide a construction for a pump wherein the impelling vanes are made in the form of so-called slippers loosely carried in notches in the periphery of the rotor with notches on the rotor serving only to drive the

vanes, and the vanes or slippers being of such size and shape as to allow a passage of the fluid to the under side of the slipper members, thereby to make available the pressure existing in the fluid being pumped to hold the slippers in contact with the surface of the pump chamber to produce a pumping action.

It is another object to provide vanes loosely carried by the rotor so constructed as to be freely slideable radially relative to the rotor by providing means to break such cohesive surface contacts as may be built up between the vanes and the notches in the rotor.

It is a further object to provide a pump construction employing slipper type vanes of such size and proportions as to be balanced when loosely carried in notches in the periphery of a rotor so that said vanes will efficiently produce a pumping action by being held in sliding contact with the surface of the pump housing while being subjected to fluid pressure existing in the pump housing; to the driving force of the rotor; to the centrifugal force created by rotation with the rotor.

It is another object to make use of appropriately positioned driving contacts between the loosely carried vanes and the driving rotor to make available a component of the driving force in a direction to assist movement of said vanes toward the surface of the pump housing.

It is another object to provide a pump with operating parts which are self compensating for wear.

It is a further object to make available a pump design which can be built around an existing shaft in the unit with which it is installed, the operating parts of the pump being carried near the periphery of the rotor shaft. With such a construction it is often possible to dispense with gearing between a thru shaft and the pump by placing the pump directly on the shaft.

The above and other objects of the invention will appear more fully from the following more detailed description and by reference to the drawings forming a part hereof and wherein:

Fig. 1 is a vertical transverse section taken through the pump housing and rotor.

Fig. 2 is a section taken on the line 2—2 of Fig. 1 and shows the inlet port together with the rotor and housing.

Fig. 3 is a transverse section through a portion of the rotor and housing of a pump of the type herein disclosed, showing the position and construction of a plurality of the vanes or slippers.

Fig. 4 is a section similar to Fig. 1 but includes resilient means to aid in holding the vanes or slippers in position.

Fig. 5 is another varied construction showing means to position the slippers by fluid pressure on the opposite side of the rotor.

Fig. 6 is a form of construction which may be employed for positioning the slippers by an inclined edge of the notch on the rotor.

Referring to the drawing, the pump shown in Figs. 1 and 2 comprises a rotor 1, circular in section and having axial shaft extensions 2 and 3. The shaft extension 2 is rotatably journaled in a bearing 4 in the pump body 5 which has a circular pump chamber 6 in which rotor 1 is mounted. The pump chamber 6 is eccentric with respect to the center of the rotor 1 and the chamber is closed by a cover plate 7 provided with a bearing 8 in which the shaft extension 3 is journaled. The shaft extension 3 extends beyond the end of the bearing 8, and is adapted to

have driving means connected thereto for the purpose of actuating the pump. It is understood that it would be possible to make the rotor 1 as a separate ring secured to a thru shaft, in which case the pump could be easily adapted for assembly on a shaft available in a motor or other unit without the provision of additional gearing or other driving means.

The rotor 1 has a plurality of notches 9 in its periphery, preferably spaced at unequal intervals. Slippers 10, which are substantially narrower than the notches 9, are disposed loosely in the notches, and are provided with outer surfaces having a curvature corresponding to the curvature of the chamber 6. The inner surfaces of the slippers have projections 11 adapted to contact bottom surfaces of the notches to prevent a flat surface contact between the inner faces of the slippers and the bottom surfaces of the notches.

An intake port 12 and an outlet port 13 are provided in the pump body, at substantially diametrically opposite points, the intake port 12 having extensions 14, and the outlet port having extensions 15, all extending circumferentially of the pump chamber 6. The intake and outlet extensions 14 and 15 are separated adjacent the point of tangency 16 between the rotor 1 and the pump chamber 6, as indicated at 17, the arcuate width of said separation being slightly greater than the width of any notch 9. The other ends of the extensions 14 and 15 are separated an arcuate distance greater than the arcuate distance between any two slippers, and this space constitutes the working zone.

As the shaft extension 2 is driven to rotate the rotor 1, centrifugal force acts upon the slippers 10 and forces them into contact with the wall of the pump chamber 6, and they are impelled around the pump chamber by the trailing edges 18 of the notches 9. The slippers are thus caused to move the fluid from the intake port 12 to the outlet port 13, and the pressure under which the fluid is placed during movement through the working zone acts on the inner faces of the slippers to augment the action of centrifugal force in holding the slippers in contact with the wall of the pump chamber.

As will be noted on reference to Figs. 1 and 3, the slippers 10 are circumferentially long as compared with the greatest radial distance between the point at which slipper 10 contacts the notch in the rotor and the wall of the pump chamber. Such a construction assures that there will be a sufficient exposed inner surface on each slipper so that the fluid pressure action on the slipper will always counteract the tendency of the driving force applied by the notch 9 to tilt the slipper away from seating contact with the bore. As viewed in Figs. 1 and 3, the action of the driving surfaces of the notches 9 would tend to produce a tilting of the slippers in a clockwise direction and therefore would tend to tilt the trailing edges of the slippers away from contact with the bore. However, if the slippers are sufficiently long, circumferentially, the fluid pressure action on the exposed inner surface of each will be sufficient to overcome the tilting action of the driving force of notches 9 and as a result the slippers will be continuously held in sliding surface contact with the pump chamber bore. As a further aid in counteracting this tendency to tilt, the trailing edge of each slipper may be relieved or chamfered, as indicated at 18 in Fig. 3. Such a change in shape will tend to set up a counter-clockwise tilting tendency induced by the

action of fluid pressure on the inner surface of the slipper, the slipper tending to tilt about the trailing edge of its contact with the pump bore. By proper proportioning, the tilting effect of the driving notch can be counteracted to the desired degree. Probably a slight counter-clockwise tilting tendency is desirable to facilitate the entrance of an oil film between the slipper and the bore. The amount of this tendency can be controlled with suitable changes in proportions by employing the principles above outlined.

Referring to Fig. 3, which illustrates the operation when a plurality of blades are passing simultaneously through the working zone, it may be observed that the slippers 10a in being loosely mounted in notches 9a in the rotor 1a, are free to move away from the trailing edges of their respective notches. The slippers ahead and behind the central slipper in Fig. 3 are free to move away from the driving edges of their respective notches to permit the fluid to pass as the slippers are carried through the working zone. It is to be noted that this ability of the slippers to bypass fluid makes possible the use of ports which are spaced farther apart than the slippers which in turn makes possible unequal spacing of slippers and prevents the occurrence of uniform impulses, the presence of which might otherwise tend to produce a resonance.

It is further to be noted that the ability of adjacent slippers to bypass fluid to compensate for unequal displacement of fluid effects a smooth transfer of pumping load from one slipper to another. Such a controlled and uniformly smooth transfer of load is a material factor in reducing noise in this type of pump. Considering the slippers shown in the working arc Fig. 3 the central slipper, of the three shown, is near the center of the working arc and therefore is displacing fluid at a greater rate than the other two slippers, both being shown in Fig. 3 as bypassing fluid. As the rotor brings the right hand slipper toward the center it will gradually assume a position in contact with the driving edge of its notch which condition will be effected when the right hand slipper and the central slipper reach a position equally distant from the part of the working arc where there is greatest distance between the rotor and the bore. At such a position both slippers will be momentarily in contact with their driving notches. However during further rotation the entire load will be smoothly transferred to the right hand slipper of Fig. 3. The load will be transferred in turn to the next slipper.

Fig. 4 illustrates springs 19 mounted in the rotor 16, the springs acting against the slippers 10b to yieldingly hold the slippers in contact with the wall of the pump chamber 6b. The springs are desirable to keep the slippers in contact with the housing in cases where centrifugal force is not sufficient for this purpose due to a low speed of operation of the pump and in cases where very viscous fluids are being pumped.

I have shown in Fig. 5 an alternative construction to that of Fig. 4 and wherein a push rod 20 is slidably mounted in a bore in the rotor 21 with its opposite ends projecting into substantially opposite notches 22. The ends of the rod 20 lie adjacent the slippers 23 in respective notches 22, and while one slipper is passing through the intake zone fluid pressure in the working zone acts upon the remote end of the rod to force the rod against the opposite slipper and to force it into contact with the wall of the pump chamber. The use of a round rod makes possible the use of

a round reamed hole in the shaft which is more easily accomplished in manufacture, than other shapes. This construction may be used with pumps having an even number of slippers. The fundamental principle involved in the use of fluid pressure existing on the opposite side of the rotor to assist in positioning a thru type of vane having a length less than the shortest distance across the bore, is disclosed and claimed in my co-pending application, Serial #220,308. The specific disclosure of Figure 5, herein, is further development as applied to the slipper type of vane disclosed in this application.

As shown in Fig. 6, the rotor and slipper may be so constructed that the rotation of the rotor will tend to push the slipper outwardly when contact is made by the notch with the edge of the slipper. In Fig. 6 slipper 25 is shown provided with a trailing edge 26 inclined at a considerable angle with both the radius of the bore and the radius of the rotor. The notch 27 in the rotor has the face 28 which contacts the trailing edge 26 of the slipper also inclined at an angle which corresponds to the angle of the edge 26. If it be assumed that the rotor in Fig. 6 is rotating in a counterclockwise direction, it will be apparent that because of the inclination of the contacting surfaces 26 and 28 the rotation of the rotor will produce a component of force which will push the slipper 25 outwardly to contact the pump chamber.

Another feature of the construction, as shown in Figs. 1 and 3, is the tendency of the slippers to assume such a position relative to the driving edges of the notches that the rear edge surfaces will be inclined relative to a radius of the rotor in such direction that an outward component of the driving force from the rotor tends to force the slipper radially outward. Such an inclined position is shown at 30 in Fig. 1.

It is noted that the slippers do not fit in their respective notches with too close dimensions but that the notches are actually very much larger than the width of the slippers. In fact, every precaution is taken to assure that the slippers will not adhere because of surface contact to any part of the notches, projections $\dagger$ even being provided in the center of the inner surface of the slippers to break the long surface contact which would otherwise occur between the inner surface of the slippers and the bottom of the notches. There is therefore no force required to break the slippers away from contact with the notches but they are at all times free to slide outwardly with the action of a small force.

When a pump of the type herein described is started, centrifugal force tends to bring the slippers into contact with the bore, as the slippers are pushed around by the trailing or driving edges of the notches in the rotor. It is characteristic of the pump, herein disclosed, that the slippers or vanes fit loosely in the notches and such contact as occurs between the notches and the slippers is only such as is necessary for driving. As the slippers 10a Fig. 3 are carried thru the working arc they move fluid from the intake port to the outlet port and whatever pressure is built up in the outlet is transmitted to the space under the slippers, and acts in addition to centrifugal force to press them against the bore which further assures an effective seal between each slipper and the pump bore. To improve the seal the outside of the slipper is machined to the same curvature as the bore. This makes film lubrication possible between the two sur-

faces and a minimum of wear results. However any slight wear which does occur is compensated for by movement of the slippers 10a further outward in the notches 9a.

It has been found necessary to provide unobstructed passage for fluid to flow to and from the space between the notch and the slipper as otherwise the dash-pot action of the slippers in their notches prevents them from following the bore during the "intake arc" when there is no fluid pressure under them, thereby causing noise and loss of pressure. The slippers are therefore given a wide clearance, circumferentially in the notches, the inner leading edges 29 (Fig. 1) are chamfered or otherwise formed to permit oil to flow freely around them. The previously mentioned projections 11 (Figs. 1 and 2) are also provided on the bottom of the slippers to assure that oil will always be free to flow under them thus permitting centrifugal force to lift the slipper freely outward in the notch. A further reason for the use of the projections is to prevent contact of the surfaces and to prevent formation of an oil film between the bottom of the notch and the slipper which would cause the surfaces to stick together.

As shown in Fig. 3, the slippers may be positioned with unequal spacing between the plurality of slippers used. This uneven spacing has been found beneficial in preventing undue noise in the pump since unevenly spaced impulses do not cause a hum, resonance or musical note. It is noted that because of loose slipper construction the relation between the distance between the ends of the ports and the distance between the vanes or slippers need not be accurate as long as the distance between the vanes is always less than the maximum distance between the ports. With such a construction the inlet and outlet can be cast without any requirement for subsequent machining to insure accuracy in the distance between the ports which was so necessary in previous practice.

Although the principles of the invention have been illustrated by a description of a specific mechanism it is understood that various changes and modifications may be made without departing from the fundamental principles as indicated by the scope of the following claims.

I claim:

1. In a pump, a pump casing having a pump chamber of cylindrical configuration and having an inlet and outlet positioned on opposite sides thereof, a rotor mounted for rotation in the pump chamber and having a plurality of notches in the periphery thereof, a vane mounted in each of said notches and having circumferential width and radial depth less than the circumferential width and radial depth of said notches, respectively, whereby said vanes are carried in said notches with freedom of circumferential, tilting and radial movement relative to said rotor, each of said vanes having an outer arcuate surface curved on an arc of substantially the same radius as said cylindrical chamber and said vanes having greater circumferential width than radial depth whereby fluid pressure admitted at the under side of said vanes through the space between each vane and the respective notch acts on a greater area on said under side than on the front thereof to insure sealing contact of the arcuate outer face of said vanes along a substantial surface area, the maximum distance between two adjacent vanes and between two adjacent notches of said rotor being less

than the maximum distance between the inlet and outlet of said pump casing.

2. In a pump, a pump casing having a pump chamber of cylindrical configuration and having an inlet and outlet positioned on opposite sides thereof, a rotor mounted for rotation in the pump chamber and having a plurality of unequally spaced notches in the periphery thereof, a vane mounted in each of said notches and having circumferential width and radial depth less than the circumferential width and radial depth of said notches, respectively, whereby said vanes are carried in said notches with freedom of circumferential, tilting and radial movement relative to said rotor, each of said vanes having an outer arcuate surface curved on an arc of substantially the same radius as said cylindrical chamber and said vanes having greater circumferential width than radial depth whereby fluid pressure admitted at the under side of said vanes through the space between each vane and the respective notch acts on a greater area on said under side than on the front thereof to insure sealing contact of the arcuate outer face of said vanes along a substantial surface area, the maximum distance between two adjacent vanes and between two adjacent notches of said rotor being less than the maximum distance between the inlet and outlet of said pump casing, the freedom of circumferential movement and radial tilting of said vanes in said notches permitting by-passing of said fluid around the under side of said vanes while the outer surface thereof is maintained in contact with the inner wall of said casing.

3. In a pump, a pump casing having a pump chamber of cylindrical configuration and having an inlet and outlet positioned on opposite sides thereof, a rotor mounted for rotation in the pump chamber and having a plurality of notches in the periphery thereof, a vane mounted in each of said notches and having circumferential width and radial depth less than the circumferential width and radial depth of said notches, respectively, whereby said vanes are carried in said notches with freedom of circumferential, tilting and radial movement relative to said rotor, each of said vanes having an outer arcuate surface curved on an arc of substantially the same radius as said cylindrical chamber and said vanes having greater circumferential width than radial depth whereby fluid pressure admitted at the under side of said vanes through the space between each vane and the respective notch acts on a greater area on said under side than on the front thereof to insure sealing contact of the arcuate outer face of said vanes along a substantial surface area, the maximum distance between two adjacent vanes and between two adjacent notches of said rotor being no greater than the maximum distance between the inlet and outlet of said pump casing, each of said vanes having the trailing edge of their outer curved portion relieved to increase the tilting effect of the slipper about its trailing edge to insure sealing contact with the outer surface thereof with said pump casing.

4. In a pump, a body portion formed with a pump chamber wall and a fluid inlet and fluid outlet, a rotor mounted for rotation in said chamber having a plurality of notches cut in the periphery thereof, vanes of circumferential width substantially less than the width of said notches loosely carried in said notches with freedom of radial and circumferential movement relative to

said notches, each of said vanes having an outer arcuate surface of a radius substantially equal to the radius of the wall of said pump chamber and adapted to have substantial surface contact with said pump chamber wall, and means for admitting the fluid pressure in said pump chamber to the under side of said vanes to cooperate with the centrifugal force resulting from rotation of said pump to hold said vanes in intimate sealing contact with the inner wall of said chamber, said notches being of a size and spacing such that the maximum allowed spacing between said vanes is less than the maximum distance between said inlet and outlet.

5. In a pump, a body portion formed with a pump chamber wall and a fluid inlet and fluid outlet, a rotor mounted for rotation in said chamber having a plurality of notches cut in the periphery thereof, vanes of circumferential width substantially less than the width of said notches loosely carried in said notches with freedom of radial and circumferential movement relative to said notches, each of said vanes having an outer arcuate surface of a radius substantially equal to the radius of the wall of said pump chamber and adapted to have substantial surface contact with said pump chamber wall, means for admitting the fluid pressure in said pump chamber to the under side of said vanes to cooperate with the centrifugal force resulting from rotation of said pump to hold said vanes in intimate sealing contact with the inner wall of said chamber, said notches being of a size and spacing such that the maximum allowed spacing between said vanes is less than the maximum distance between said inlet and outlet, and means for preventing said vanes from sticking on their under sides to the bottom of said notches.

6. In a pump, a body portion formed with a pump chamber wall and a fluid inlet and fluid outlet, a rotor mounted for rotation in said chamber having a plurality of notches cut in the periphery thereof, vanes of circumferential width substantially less than the width of said notches loosely carried in said notches with freedom of radial and circumferential movement relative to said notches, each of said vanes having

an outer arcuate surface of a radius substantially equal to the radius of the wall of said pump chamber and adapted to have substantial surface contact with said pump chamber wall, means for admitting the fluid pressure in said pump chamber to the under side of said vanes to cooperate with the centrifugal force resulting from rotation of said pump to hold said vanes in intimate sealing contact with the inner wall of said chamber, said notches being of a size and spacing such that the maximum allowed spacing between said vanes is no greater than the maximum distance between said inlet and outlet, and means for preventing said vanes from sticking on their under sides to the bottom of said notches comprising relieved portions on the under sides of said vanes.

7. A pump of the type employing a rotor mounted eccentric to a substantially circular pump chamber having an inlet and outlet communicating with the walls of the pump chamber characterized by a plurality of vanes with maximum allowed spacing less than the maximum distance between said inlet and outlet each driven by contact with a notch in said rotor but having freedom of movement circumferentially, radially and angularly with respect to said notch and having a configuration such as to provide passages to admit fluid under pressure to the inner surfaces and around said vanes, each of said vanes having an outer surface of arcuate shape curved on the same radius of curvature as the pump chamber so that said driving contact on said vanes by said notches combined with fluid pressure and centrifugal force position said outer curved surfaces of said vanes in stable equilibrium against the inner surface of the said pump chamber in spite of the tendency of the driving force exerted by said rotor to tilt the said outer surface of said vane away from said chamber surface and the circumferential movement of said vanes relative to said notches allowing by-passing of fluid around said vanes while said outer vane surfaces are maintained in contact with said pump chamber surface.

WILLIAM T. LIVERMORE.
